GAS-BURNER CONTROL SYSTEM

William A. Ray, North Hollywood, Calif., assignor
to General Controls Co., Glendale, Calif., a corporation of California

Application April 1, 1947, Serial No. 738,510

6 Claims. (Cl. 158—117.1)

1

My present invention relates to gas-burner control systems, and more particularly to an improved valve structure for controlling such a system. Conventional valves, of the type to which the structure of this invention pertains, include a safety-valve, biased to closed position and manually-openable, and means, responsive to the flame of the burner controlled by the valve, for retaining the valve in open position while the flame exists.

It is an object of this invention to combine, with a valve of the type described, electrical means for igniting the gas at the burner.

Another object is to provide a valve structure having a single actuating-means or handle for controlling both the opening of the safety valve and the igniting of the gas.

Another object is to arrange the manual control means so that the production of an electric spark or equivalent effect can be repeated, as many times as may be necessary to ensure ignition of the gas, without moving the safety-valve from its fully-open position, so that the flow of gas is uninterrupted and the safety-valve is in condition to be retained by the flame-responsive means immediately upon establishment of the flame.

For full understanding of the invention, and further appreciation of its objects and advantages, reference is to be had to the following detailed description and accompanying drawing, 30 and to the appended claims.

In the drawing:

Figure 1 is a sectional view of a valve structure embodying the invention;

Figure 2 is a section taken generally along the irregular line 2—2 of Fig. 1;

Figure 3 is a bottom view of the structure shown in Figs. 1 and 2, taken in the plane of line 3—3 of Fig. 2;

Figure 4 is a sectional view of the manual actuating means, taken along the line 4—4 of Fig. 2;

Figure 5 is a schematic view of a gas-burner control system including the valve structure shown in Figs. 1—4; and

Figure 6 is a chart showing the angular positions of handle 53 corresponding to the various control operations.

In the drawing, the numeral 11 indicates a valve casing having an inlet 12 and a main outlet 13, communication between which is controlled by a tapered plug 14 seated in a conforming opening in the casing and having a flow-controlling passage 15 adapted, in the rotation of the plug, to be placed in and out of register with passages 16 and 17 leading to the inlet and main outlet, respectively, of the casing. Branching from the passage 16 is a restricted supplemental-outlet passage 18 which communicates with a pipe 19 shown in Figs. 2, 3 and 5.

In the inlet chamber 20 of the valve casing is a

6 safety-valve comprising a disk-like closure 21, cooperable with a circular seat raised at the inlet end of passage 16, and carried by an angled lever 22 of channeled construction; the closure having a turned-up ear portion 23 which is connected to the lever by a pin 24 so that the closure can rock slightly to conform to its seat. Supporting the lever 22 is a bracket having, as seen in Fig. 2, spaced side-portions 25 which are secured by screws 26 to bosses 27 projecting from the wall of the upper portion of the inlet chamber 20. Extending upwardly from the bracket-portions 25 are arms 28 spaced to receive the lever 22 and supporting a pin 29 on which the lever is pivoted. At their left-hand ends (as viewed in Fig. 1) the bracket-portions 25 are bent downwardly and toward each other to form an abutment 30 for the upper end of a compression spring 31 whose bottom end bears against the horizontal surface of a shallow depression in the top of the plug 14, thereby maintaining the plug properly seated; a washer 32 being interposed between the spring and the bracket. Depending from the bracket-portions 30 is a cup-like receiver 33 (the upper portion of which is apertured at its sides as viewed in Fig. 1) for the lower end of a spring 34 whose upper end bears, through a cup 35, against the downwardly-bent pointed extremity 36 of the left-hand end of lever 22, thereby biasing the lever to closure-seating position.

The squared stem 37 of the plug 14 is within an elongated opening, through the bottom wall of the valve casing, encompassed by a tubular extension 38. Within the extension is a cupped member 39 having in its end wall an opening fitting the plug-stem 37; four spaced fingers 40 extending outwardly and downwardly from the rim of the cup, as is better seen in Fig. 4. Around the extension 38 is a sleeve 41, to the flared top end of which a ball-race 42 is secured as by welding. This race, together with balls 43, forms a ball-bearing support for the sleeve and is held in place by a snap-ring 44 cooperating with a shoulder formed on the extension 38. Providing a 45 lost-motion connection between the sleeve 41 and the plug-operating member 39 is an arm 45, dished slightly at the middle, whose opposite extremities are received in conforming slots in the sleeve 41 (Fig. 4); the inner portions of the arm 45 lying between the fingers 40 of member 39. Secured to the arm 45, by a screw 46, is an inner cap 47 fitting over the sleeve 41 and whose side wall is provided with projections 48 (Fig. 4) which form inner recesses for receiving the extremities 55 of arm 45, thereby providing a driving connection between the cap 47 and arm 45 independent of screw 46; there being extra projections 48' so that, if desired, the cap can be mounted in another position at 90° to that shown. From the foregoing it is clear that the cap 47, arm 45 and

sleeve 41 are so interconnected that they are rotatable as a unit on the ball-bearing.

Surrounding the inner cap 47 is an outer cap 49 whose side wall is formed to provide inward projections 50 (Fig. 4) engageable with the projections 48-48' of the inner cap 47, the outer cap being freely mounted on the screw 46 so that it can be rotated with respect to the inner cap 47 through an angular distance (approximately 45°) determined by the distance between the projections 48-48'. Biasing the outer cap 49 in a counterclockwise direction (as viewed in Fig. 4) with respect to the inner cap 47 is a relatively-stiff coil-spring 51 (Figs. 1 and 3) which is welded at its outer end to the side wall of the outer cap, and at its inner end to an angle-bracket 52 secured to the end wall of the inner cap. Projecting integrally from the outer cap 49 is a handle 53 which constitutes the outer cap a handle member.

Formed integrally with the sleeve 41 and projecting laterally from the top rim thereof is a lug 54 which, as can be seen in Fig. 2, cooperates with a small bell-crank lever 55 disposed partially within a slot 56 (Fig. 3) milled in a thickened outer portion of the valve casing, and pivoted on a pin 57. Engageable by the right-hand arm of the bell-crank 55 is a rod 58, reciprocable in a vertical opening in the casing leading to the inlet chamber 20, and whose upper end cooperates with a lateral extension of the upper part of the closure-lever 22. To prevent escape of gas around rod 58, the opening for this rod is counterbored at its upper end to receive a spring 60 which serves to compress a soft washer 61 around the rod-opening; the upper portion of the spring bearing against an arm 62 having an opening for the rod, which arm is formed as an extension of one of the bracket-portions 25.

Formed as a lateral projection of the rim of the outer cap 49 is another lug 63 which carries a finger 64; the finger being pivoted on a pin 65 and normally held, by a torsion spring 66, with its rear portion in engagement with a stop-pin 67, so that when the cap 49 is rotated in clockwise direction (as viewed in Fig. 3) the finger 64 acts as a rigid extension of the lug 63, but is yieldable when the cap 49 is rotated in the opposite direction.

Mounted on the valve casing by means of an angle-bracket 68, and generally indicated at 69, is a magneto having a stem 70 to which is secured an actuating-arm or trigger 71. This magneto may be of conventional design and its structural details are not disclosed since they have no bearing on the present invention. It suffices to state that the trigger 71, as shown in solid lines in the drawing, is in a stopped position to which it is biased, and when the trigger is moved from this position to its broken-line position shown in Fig. 3, mechanical energy is stored in the magneto, which energy, when the trigger is then released and snaps back to its former position, is translated, by means of a coil 72 mounted on the frame 73 of the magneto, into electrical energy of potential high enough to produce a spark or series of sparks between suitably-spaced electrodes connected to the coil.

Covering the open top of the valve casing 11 is a diaphragm 74, of flexible material such as leather, which is clamped at its margin between the casing and the flanged mouth of a housing 75 secured to the casing. Forming within housing 75 an extension of the closure-lever 22 is a chan-

neled arm 76 which is secured to the lever, by screws 77, with diaphragm 74 therebetween; the connection between these parts being gas-tight. A disk-shaped armature 78 is rockably mounted on the arm 76 by means of a headed pin 79 riveted to the arm and freely extending through a central opening in the armature; a compression spring 80 urging the armature against the head of the pin. Cooperable with this armature, and secured to the top wall of housing 75, is an electromagnet comprising a U-shaped core 81 and an energizing coil 82, the leads of which are connected to terminal posts 83 insulatingly mounted in the side wall of the housing. The electromagnet is incapable of attracting the armature through space but is adapted, when energized and the armature is first mechanically brought into engagement with the pole-faces 84, to magnetically hold the armature and thereby the closure-lever against the bias exerted by spring 34.

Referring now to the burner-control system shown in Fig. 5, the numeral 85 indicates a main gas-burner which is connected by a pipe 86 to the main outlet 13 of the valve casing. For igniting the main burner there is a pilot burner 87 connected to the pipe 19 which, as previously described, leads to the supplemental outlet 18 shown in Fig. 1. Mounted on the pilot burner, so that its tip is subjected to the flame thereof, is a thermocouple 88 adapted when heated to generate electricity in a well-known manner, the thermocouple being connected by wires 89 to the terminal posts 83 of the electromagnet 81-82. Also mounted on the pilot burner, by an arm 90, is a spark-plug 91 for igniting the pilot burner and whose insulated electrode is connected by a wire 92 to one lead 93 of the magneto-coil 72, the other lead of this coil being internally grounded to the frame of the magneto so that the high-tension circuit for the spark-plug is completed through the metallic parts of the system.

Assuming that the inlet 12 of the valve casing is connected to a supply of fuel-gas, with the parts in the positions shown in the drawing flow of gas to both the main and the pilot burner is obstructed by the closure 21; the handle 53 then being in the position indicated by the line 94 in the chart of Fig. 6. If the handle member 53, 49 is now manually rotated in clockwise direction (as viewed in Figs. 3, 4 and 6) force is applied through coil-spring 51 to the unit consisting of inner cap 47, arm 45 and sleeve 41, causing rotation of this unit so that the bell-crank 55 is rocked by the lug 54 to effect upward movement of rod 58 and rocking of the closure-lever 22 (and its extension 76) to a position wherein movement of these parts is limited by the engagement of armature 78 with the pole-faces 84 of the electromagnet (or by the engagement of the bell-crank with the floor of slot 56); the plug 14 also being rotated in this operation (through the arm 45 and the fingers 40 of the plug-operating member 39) but not sufficiently to bring the plug-opening 15 into communication with the passages 16-17, it being obviously desirable that flow of gas to the main burner be prevented until the pilot burner is lighted. The coil-spring 51 in the handle member is of such stiffness that it does not yield appreciably during the foregoing operation, so that the handle 53 is in the position indicated by the chart-line 95 at the conclusion of the operation; the angular distance between the lines 94 and 95 corresponding to the arc through which the sleeve 41 is moved.

It is to be observed that if the handle 53 is released when it is in the position of chart-line 95 (assuming that the electromagnet is unenergized) all of the parts, with the exception of the plug and its operating member 39, will return under the force of the bias spring 34 to the positions shown in the drawing; the lost-motion connection afforded by the spaced fingers 40 eliminating the frictional load which otherwise would be imposed by the plug.

Due to the yieldable connection afforded by the coil-spring 51, the handle member can be rotated in clockwise direction beyond the position indicated by the chart-line 95 (the inner cap 47 and the parts operated thereby remaining in their arrested positions) so that the finger 64 engages the magneto-trigger 11 and moves it to its broken-line position from which position (indicated by chart-line 96), when the finger 64 is rotated slightly farther, the trigger snaps back to effect production of a spark (as described above) at the electrodes of the spark-plug 91, which spark ignites the gas now flowing (since closure 21 is unseated) to the pilot burner.

Should the spark fail to ignite the gas at the first attempt, the operation can be repeated as many times as necessary, without effecting disengagement of the armature 18 from the pole-faces 84, by first rotating the handle backwardly to a position wherein the finger 64 can pass behind the trigger 11, that position being indicated by the chart-line 97.

When flame is established at the pilot burner, the handle is maintained in operated position until the thermocouple has become heated to a temperature such that electricity is generated by the thermocouple in an amount sufficient to cause the electromagnet to hold the armature, whereupon the handle may be released; the lever 22 then being magnetically retained in closure-open position, while the pilot flame exists. To supply gas to the main burner, the handle is rotated in counterclockwise direction to the position indicated by the chart-line 98, corresponding to the fully-open position of the plug, or to some position between the chart-lines 98 and 99 if it is desired to throttle flow to the main burner. In the initial clockwise rotation of the handle from the position of chart-line 98 the lost-motion, due to the spacing of fingers 40, is taken up, as is indicated by the chart-line 100. In the event of extinguishment of the pilot-burner flame, upon cooling of the thermocouple and resultant de-energization of the electromagnet, the armature is released so that the safety-valve, comprising lever 22 and closure 21, closes under the force of bias-spring 34, thereby completely obstructing flow through the valve casing; it then being necessary to reinitiate operation of the system in the manner described above.

The specific embodiment of my invention herein shown and described is obviously susceptible of modification without departing from the spirit of the invention, and I intend therefore to be limited only by the scope of the appended claims.

I claim as my invention:

1. In a gas-burner control system: a burner; a valve for controlling supply of gas to said burner and having a closure biased to closed position; manually-operable means for opening said valve and including a handle member movable to a position wherein said closure is open; means limiting the movement of said valve-opening means when said handle member is in said position;

tion; a resilient connection between said valve-opening means and said handle member, said connection being relatively unyielding in the opening of the closure but yielding to permit continued movement of the handle member beyond said position; electrical means, operated by said continued movement of the handle member, for igniting the gas at said burner; and means responsive to the flame of said burner for holding said closure in open position against the force of said bias while said flame exists.

2. The combination defined in claim 1, and wherein said gas-igniting means comprises mechanical means, operated by said continued movement of said handle member, for generating electricity.

3. The combination defined in claim 1, and wherein said gas-igniting means comprises a magneto adapted to produce a spark at said burner and operated by said continued movement of said handle member.

4. In a gas-burner control system: a burner; a valve for controlling supply of gas to said burner and having a closure; an arm movable to open said closure and biased to a position wherein the closure is closed; an armature carried by said arm; an electromagnet engageable by said armature when said arm is in closure-open position and thereby limiting movement of the arm, said electromagnet being adapted when energized to magnetically hold said armature and thereby retain said arm in closure-open position against the force of said bias; manual means, including a handle member, for moving said arm to closure-open position; a resilient connection between said arm and said handle member, said connection being relatively unyielding in the movement of the arm to closure-open position but yielding, when the movement of the arm is limited, to permit continued movement of the handle member; electrical means, operated by said continued movement of the handle member, for igniting the gas at said burner; and means responsive to the flame of said burner for effecting energization of said electromagnet so that said arm is retained in closure-open position while the flame exists.

5. The combination defined in claim 4, and wherein said gas-igniting means comprises mechanical means, operated by said continued movement of said handle member, for generating electricity.

6. The combination defined in claim 4, and wherein said gas-igniting means comprises a magneto adapted to produce a spark at said burner and operated by said continued movement of said handle member.

WILLIAM A. RAY.
